VARIABLE DELIVERY PUMP

Max A. Mathys, Detroit, Mich., assignor to Ex-
Cell-O Corporation, Detroit, Mich., a corpora-
tion of Michigan

Original application February 17, 1941, Serial No.
379,211. Divided and this application Novem-
ber 15, 1946, Serial No. 710,153

6 Claims. (Cl. 103—162)

1

The present invention relates to improvements in rotary pumps of the swash plate type.

One of the objects of the invention is to provide a pump of the foregoing type in which the swash plate is controlled to counterbalance the hydraulic reaction in the pump cylinders, and is further subject to adjustment in response to fluid pressure to vary the pump displacement selectively from zero to maximum.

Another object is to provide a variable delivery swash plate pump which is simple in construction, and capable of sensitive and accurate control in displacement.

Further objects and advantages will become apparent as the description proceeds.

In the accompanying drawings,

Figure 1 is a fragmentary side view, partially in vertical section, of a machine unit incorporating a pump embodying the features of the present invention.

Figs. 2 and 3 are views of the pump valve taken respectively in the directions of the arrows 2—2 and 3—3 of Fig. 1.

Fig. 4 is a fragmentary horizontal sectional view taken along line 4—4 of Fig. 1.

Fig. 5 is a fragmentary vertical sectional view taken along line 5—5 of Fig. 4.

Fig. 6 is a diagrammatic representation of the pump.

The pump, constituting the exemplary embodiment of the invention, is shown as incorporated in hydraulic power unit disclosed and claimed in my copending application, Serial No. 379,211, filed February 17, 1941 (now patent No. 2,416,339), of which the present application is a division. Consequently, the pump utilizes as its housing the external housing 7 of the power unit.

The pump is of the type having parallel annularly arranged piston and cylinder units, and is mounted on the inside of a gear case 8 closing one end of the housing 7. In its preferred form, the pump comprises a stationary valve member 9 and a rotary cylinder body 10, having flat annular end valve faces 11 and 12 in rotary bearing engagement. The valve member 9 has the form of a cylindrical plug tightly pressed into a bore 13 in the gear case 8, and is located radially by means of a spline screw 14 projecting from the case into a groove 15. The inner end of a drive shaft 16 extends freely through an axial bore 17 in the valve plug 9 into an axial bore 18 in the cylinder body 10. Formed in the bore 18 are internal splines 19 which interfit slidably with longitudinal splines 20 on the inner end of the

2

shaft 16 to establish the drive connection for the pump, and which are relatively short so as to permit a limited amount of peripheral float of the cylinder body 10 and thereby ensure accurate seating of the valve faces 11 and 12.

Formed in the cylinder body 10 in parallel uniformly spaced relation about the bore 18 are a plurality of pump cylinders 21 having cylinder ports 22 opening from the inner ends to the valve face 12. Suitable pump pistons or plungers 23 are respectively reciprocable in the cylinders 21. The plungers 23 are urged outwardly by coiled compression springs 24. These springs engage the inner ends of the cylinders 21, and extend into bores 25 in the inner ends of the plungers 23 so that the latter may be comparatively short in length.

A swash plate 26 having a flat bearing face 27 is in operative association with the outer ends 20 of the plungers 23, and when inclined is adapted to cause reciprocation of the plungers in uniformly timed sequence upon rotation of the cylinder body 10. Bearing shoes 28 are connected by means of suitable inserts 29, for universal 25 pivotal adjustment, to the outer ends of the plungers 23, and have flat faces in sliding engagement with the bearing face 27 of the swash plate 26. The swash plate 26 is mounted in the housing 7 on a pivot pin 30 at one end for 30 angular adjustment about an axis extending transversely of the axis of rotation of the cylinder body 10. Preferably, the pin 30 is located at a point adjacent the axis of each plunger 23 as the latter reaches top dead center position at the 35 end of the pressure stroke. As a result, the inward limit of movement of the plungers 23 is substantially constant and close to the inner ends of the cylinders 21.

In operation, the pump will discharge continuously, and the rate of discharge will be substantially constant for any given setting of the swash plate 26. If the angular position of the swash plate 26 is changed, the length of the plunger stroke will be adjusted to vary the rate and volume of pump displacement. When the plate 26 is adjusted into a plane perpendicular to the shaft 16, no reciprocation will be imparted to the plungers 23 and the pump displacement will be zero. In the reciprocation of the plungers 23, those on the suction stroke take in fluid from a line 31, and those on the pressure stroke discharge fluid to a line 32. For further details of the pump valve porting, reference may be had to Snader and Mathys Patent No 2,299,235, issued October 20, 1942.

The swash plate 26 is angularly adjustable about the pin 30 to vary the displacement of the pump. Within the broad aspects of the present invention, such adjustment may be effected by any suitable means. In the present instance, the swash plate 26 is automatically positioned in response to a predetermined control pressure. Thus, the plate 26 is automatically adjusted to reduce the pump delivery upon an increase in control pressure, and to increase the delivery upon a decrease in the pressure. The particular means for this purpose comprises a balancing plunger 33 and a control plunger 34 acting on the free end of the swash plate 26 in a direction to level off the latter against the hydraulic reaction in the cylinders 21 and the action of the return springs 24.

The pressure balancing plunger 33 (Fig. 5) is reciprocable in a bore 35 formed in the body structure 1 of the housing and extending transversely of the pin 30. One end of the bore 35 opens toward the free end of swash plate 26, and the other end is closed to define a pressure chamber 36 and is connected through a branch line 37 to the pressure line 32 of the pump. A shoe 38 is connected by means of an insert 39 for universal pivotal adjustment to the outer end of the plunger 33, and bears slidably against a flat face 40 on the rear of the swash plate 26. The diameter of the plunger 33 and the moment arm of force exerted thereby on the swash plate 26 are such that this force will substantially counterbalance the hydraulic reaction in the pump cylinders 21. Since the delivery pressure of the pump is always connected through the lines 32 and 37 to the pressure chamber 36 at the inner end of the plunger 33, the swash plate 26 will be hydraulically balanced throughout the range of pump delivery.

The control plunger 34 similarly is mounted for reciprocation in a bore 41 formed in the body structure of the housing 1 and opening transversely of the pin 30 to the rear face 40 of the swash plate 26. A shoe 42 is connected by means of a suitable insert 43 (Figs. 1 and 4) for universal pivotal adjustment to the outer end of the plunger 34, and slidably engages the face 40. A plug 44 is positioned in the inner end of the bore 41, and limits the inward movement of the plunger 34 to determine the maximum pump delivery. Opening from the inner end of the bore 41, between the plunger 34 and the plug 44, is a pump control line 45. This line may be connected to any suitable source of adjustable control pressure.

In operation, when the control line 45 is exhausted, the swash plate 26 will move into maximum delivery position as determined by the stop plug 44. If the control line 45 is connected to a source, as for example, the pump line 32, equal in pressure to or greater than the maximum required control pressure, the swash plate 26 will level off into substantial no-delivery position. If the control line 45 is connected to a source of intermediate control pressure, the swash plate 26 will move into an intermediate position to reduce the pump delivery accordingly, and any variation in the control pressure will result in a corresponding adjustment of the pump displacement. Since the hydraulic reaction in the pump cylinders 21 is counterbalanced by the plunger 33, the control pressure for normal working demands on the pump can be considerably lower than the pump delivery pressure. While a comparatively low control pressure is desir-

able, it should be sufficiently high to avoid substantial changes in the compressibility of the fluid. I have found that a sensitive control is obtained for low pump delivery, adapted for example for ordinary feed traverse of a machine tool element, when a control pressure at or above 110 pounds per square inch is employed. It will be understood of course that the range of control pressures required for adjustment of the pump displacement from zero to maximum is influenced by the cross sectional pressure area of the plunger 34, but in any event slight variation of the control pressure from a lesser to a greater pressure can effect a corresponding adjustment of the pump displacement from maximum to zero.

I claim as my invention:

1. A pump comprising, in combination, a stationary valve member having an end valve face 20 with peripherally spaced arcuate inlet and outlet valve ports, a rotary cylinder body having a plurality of annularly arranged parallel pump cylinders with end ports opening to an end valve face in flat bearing engagement with said first mentioned face, a plurality of pump plungers reciprocable in said cylinders, spring means for urging said plungers outwardly, an axial shaft for driving said body, said shaft extending freely through said stationary valve member into said body an angular swash plate coacting with the outer ends of said plungers for reciprocating said plungers in uniformly timed sequence upon rotation of said body, said cylinder ports moving successively through communication with said inlet and outlet ports upon movement of the respective plungers through their intake and pressure strokes, and interfitting splines drivingly connecting said body and the inner end of said shaft, the splines in said body being relatively short and the splines on said shaft being relatively long, said interfitting splines permitting limited relative floating movement of said body to insure uniform surface engagement between said valve faces.

2. A pump comprising, in combination, a stationary valve member having an end valve face with peripherally spaced arcuate inlet and outlet valve ports, a rotary cylinder body having a plurality of annularly arranged parallel pump cylinders with end ports opening to an end valve face in flat bearing engagement with said first mentioned face, a plurality of pump plungers reciprocable in said cylinders, spring means for urging said plungers outwardly, an axial shaft for driving said body, an angular swash plate coacting with the outer ends of said plungers for reciprocating said plungers in uniformly timed sequence upon rotation of said body, said cylinder ports moving successively through communication with said inlet and outlet ports upon movement of the respective plungers through their intake and pressure strokes, a hydraulic balancing plunger acting on said swash plate in a direction to decrease the inclination of said plate, and being responsive to the delivery pressure of the pump whereby to counterbalance the reaction of said pressure in said cylinders on said plungers, and a hydraulic control plunger acting on said swash plate in a direction to decrease the inclination of said plate and being adapted for response to a selectively variable control pressure whereby to control the displacement of the pump.

3. A pump comprising, in combination, a stationary valve member having an end valve face

with peripherally spaced arcuate inlet and outlet valve ports, a rotary cylinder body having a plurality of annularly arranged parallel pump cylinders with end ports opening to an end valve face in flat bearing engagement with said first mentioned face, a plurality of pump plungers reciprocable in said cylinders, spring means for urging said plungers outwardly, an axial shaft for driving said body, an angular swash plate coacting with the outer ends of said plungers for reciprocating said plungers in uniformly timed sequence upon rotation of said body, said cylinder ports moving successively through communication with said inlet and outlet ports upon movement of the respective plungers through their intake and pressure strokes, a hydraulic balancing plunger acting on said swash plate in a direction to decrease the inclination of said plate, and being responsive to the delivery pressure of the pump whereby to counterbalance the reaction of said pressure in said cylinders on said plungers, a hydraulic control plunger acting on said swash plate in a direction to decrease the inclination of said plate and being adapted for response to a control pressure whereby to control the displacement of the pump, and a positive stop for limiting the maximum angularity of said plate to define the maximum displacement of said pump plungers.

4. A pump comprising, in combination, a stationary valve member having an intake and a discharge outlet, a rotary cylinder body having a plurality of parallel cylinders annularly arranged about the axis of rotation and having a rotary valve member coacting with said stationary valve member for connecting said cylinders successively to said intake and discharge outlet, a plurality of pistons reciprocable in said cylinders, spring means in said cylinders tending to urge said pistons outwardly, a swash plate mounted for angular adjustment about an axis extending transversely of said axis of rotation and coacting with said pistons to effect reciprocation of said pistons in timed sequence upon rotation of said body, a balancing plunger responsive to the discharge pressure of said pump and coacting with said swash plate in a direction to counteract the hydraulic reaction on said pistons, and a second hydraulic plunger coacting with said swash plate in opposition to said spring means and adapted to adjust the angularity of said swash plate in response to variations in a control pressure whereby to adjust the displacement of said pistons.

5. A pump comprising, in combination, a stationary valve member having an intake and a discharge outlet, a rotary cylinder body having a plurality of parallel cylinders annularly arranged about the axis of rotation and having a rotary valve member coacting with said stationary valve member for connecting said cylinders successively to said intake and discharge outlet, a plurality of pistons reciprocable in said cylinders, spring means in said cylinders tending to urge said pistons outwardly, a swash plate mounted for angular adjustment about an axis extending transversely of said axis of rotation and coacting with said pistons to effect reciprocation of said pistons in timed sequence upon ro-

tation of said body, a housing structure formed with two parallel cylinder bores located at equal distances from said axis of said swash plate, the inner end of one of said bores being directly and constantly connected to the pressure discharge of the pump, a balancing plunger responsive to the discharge pressure of the pump and coacting with said swash plate in a direction to counteract the hydraulic reaction on said pistons, the other bore having a pressure control port adapted for connection to a source of a variable control pressure, and a second hydraulic plunger reciprocable in said other bore and coacting with said swash plate in opposition to said spring means and adapted to adjust the angularity of said swash plate in response to variations in said control pressure whereby to adjust the displacement of said pistons.

6. A pump comprising, in combination, a stationary valve member having an intake and a discharge outlet, a rotary cylinder body having a plurality of parallel cylinders annularly arranged about the axis of rotation and having a rotary valve member coacting with said stationary valve member for connecting said cylinders successively to said intake and discharge outlet, a plurality of pistons reciprocable in said cylinders, spring means in said cylinders tending to urge said pistons outwardly, a swash plate mounted for angular adjustment about an axis extending transversely of said axis of rotation and coacting with said pistons to effect reciprocation of said pistons in timed sequence upon rotation of said body, a housing structure formed with two parallel cylinder bores located at equal distances from said axis of said swash plate, the inner end of one of said bores being directly and constantly connected to the pressure discharge of the pump, a balancing plunger responsive to the discharge pressure of the pump and coacting with said swash plate in a direction to counteract the hydraulic reaction on said pistons, the other bore having a pressure control port adapted for connection to a source of a variable control pressure, a second hydraulic plunger reciprocable in said other bore and coacting with said swash plate in opposition to said spring means and adapted to adjust the angularity of said swash plate in response to variations in said control pressure whereby to adjust the displacement of said pistons, and a stop plug inserted in said second bore inwardly of said port for limiting the maximum angularity of said swash plate so as to define the maximum displacement of said pistons.
